WALTER S. GAINES, JR., OF EAST CLEVELAND, OHIO, ASSIGNOR TO THE REID PRODUCTS COMPANY, OF CLEVELAND, OHIO, A CORPORATION OF OHIO

CHANNEL

Application filed September 2, 1930. Serial No. 479,282.

The invention disclosed in this application relates to flexible channel for receiving and guiding window panes generally, and particularly those of motor vehicles.

At the present time, there is a tendency among automobile manufacturers toward the employment of shapes for automobile window openings other than the usual rectangular form. For example, in many instances, the upper ends of the window openings are curved or formed away from the former square cornered lines. In supplying the frames of these window openings with cushioning channel, it is necessary to provide a channel which not only has sufficient resiliency and stability to properly receive and hold the glass window pane but which also can be bent or formed about the frame opening in such a manner that it will conform nicely to the particular configuration or shape thereof. Inasmuch as the type of channel contemplated by this invention is one which includes an inner flexible metal core and suitable glass-engaging cushioning material, it is, of course, necessary to provide some means whereby the channel may be bent without permanent distortion of its transverse or cross sectional channel shape.

With the foregoing in mind, the present invention relates to a window channel comprising an inner metal core of thin spring metal provided with suitable cushioning material and shaped into general channel form to snugly receive and fit the window glass. In order to permit bending and flexing of the channel without permanently distorting its cross sectional channel shape, the metal core is provided at its side edges with suitable re-enforcing beads and with perforations adjacent each bead, said perforations being connected in pairs by slots or kerfs, each extending from one perforation of a pair to the other one thereof, thereby separating the main body of the core into transverse straps, which not only hold the beaded core edges in proper shape, but also serve to maintain the general cross sectional configuration of the channel as a whole.

The invention is set forth in the following description, drawing and claims.

Referring to the drawing, Fig. 1 is a perspective view of a portion of finished channel embodying the present invention; Fig. 2 is a perspective view of the metal core of the channel of Fig. 1; and Fig. 3 is a perspective view of a slightly modified form of channel core.

In the embodiment shown in Fig. 2, the channel core is formed of a band or strip of metal, preferably thin steel or the like, and including longitudinal side edge portions 1 each having an inwardly bent flange 2, whereby suitable beads are formed at both said side edges. These longitudinal side edge portions 1 are connected by a multiplicity of transverse strap portions 3 formed by providing the strip with a series of pairs of perforations 4 near the beaded side edges 1 and connected by cross slots 5 cut through the metal and each slot or cut extending from one perforation of a pair to the other one thereof. As will be readily understood, the perforations 4 at the ends of the cross slots 5 prevent tearing of the core metal through the longitudinally disposed side edges 1, aided more or less by the bead forming flanges 2.

The transverse or cross sectional shape of each of the two forms of channel core here illustrated is somewhat of U-form having a base and two side walls, which walls, if desired and as shown, may be bent inwardly toward each other to more firmly grip and hold the glass.

As shown in Fig. 1, this core of Fig. 2 is provided with suitable cushioning material, such as an inner layer 6 of rubber or other suitable material and an outer cover 7 of felt, fabric or the like, and said cushioning material, if desired and as shown, may entirely cover or enclose said core, although said entire coverage or enclosure is not, of course, essential.

In use, the channel may be applied to a window frame of any desired shape, the transverse cuts or slits and the cross straps 3 enabling the channel to be bent into any desired shape without materially affecting the cross sectional form thereof.

In the channel core modification shown in

Fig. 3, the transverse core slots are wider at their middle than at their ends, thereby enabling a channel in which this form of core is embodied to be more freely bent in either 5 direction.

The beaded outer side edge portions 1 of the channel side walls, when provided with suitable cushioning material, such as rubber and felt, form longitudinally disposed lips 10 for receiving and snugly engaging the glass when the channel is placed in a window frame groove. By transversely slitting or slotting the inner metallic core strip, as disclosed in Figs. 2 and 3 of this case, the channel 15 may be flexed very readily in almost any direction and such slitting and slotting is particularly useful in conforming the channel to the variously shaped window frame openings now in use or contemplated by automobile manufacturers in that the channel may be readily curved or bent nicely in a 20 plane corresponding to that occupied by the window pane.

Other features of the present invention 25 will be apparent to those skilled in the art to which it relates.

Having described my invention, I claim:

1. A window channel comprising an inner flexible sheet metal core of channel form having 30 slits extending transversely from points adjacent one edge to points adjacent the opposite edge, whereby the channel may be bent in various forms and whereby it may be twisted in the application to the window 35 frame.

2. A window channel as set forth in claim 1, characterized in that said core is provided with a perforation at each end of each of said transverse slits, said perforation being thus 40 located adjacent the edges of said core.

3. A window channel as set forth in claim 1, characterized in that said transverse slits are of sufficient width to permit flexing of said core in both directions relative to a plane 45 passing between the sides of said core.

4. A window channel as set forth in claim 1, characterized in that the edges of said core are provided with re-enforcing beads.

5. A window channel as set forth in claim 50 1, characterized in that each of said transverse slits is wider at its middle than at its ends.

In testimony whereof I hereby affix my signature.

55 WALTER S. GAINES, JR.
